INVENTOR.

George P Clark

UNITED STATES PATENT OFFICE.

GEORGE P. CLARK, OF JAMAICA PLAIN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELET-SETTING MACHINE.

1,282,192.

Specification of Letters Patent. Patented Oct. 22, 1918.

Application filed February 2, 1916. Serial No. 75,829.

To all whom it may concern:

Be it known that I, GEORGE P. CLARK, a citizen of the United States, residing at Jamaica Plain, in the county of Suffolk and State of Massachusetts, have invented certain Improvements in Eyelet-Setting Machines, of which the following description, in connection with the accompanying drawings, is a specification, like reference characters on the drawing indicating like parts in the several figures.

This invention relates to machines for setting eyelets or other fastening devices in sheet material and more particularly to machines for setting blind or invisible eyelets in the uppers of boots and shoes.

In setting invisible eyelets in a shoe upper the outer and lining parts of the upper are perforated and the eyelets are set in the lining part in register with the holes in the outer part of the upper. In setting blind eyelets the operation is reversed and the eyelets are set in the outer part of the upper in register with holes punched through the lining part. An object of the present invention is to provide a machine by which the operations incident to setting either blind or invisible eyelets may be carried out with improved accuracy and despatch. An important feature of the invention consists in a movable head carrying a coöperating punch and punching die, said punch and die being relatively movable to perforate the work and then movable with the head to feed the work. This construction is advantageous in that a particularly clean cut hole is formed in the outer part of the upper so that a pleasing appearance is imparted to the upper.

As herein shown, the punch is arranged to pass entirely through the punching die and to coöperate with a stationary cutting block in perforating the lining part of the upper. This arrangement constitutes another feature of the invention which it is believed is broadly novel.

These and other features of the invention will be best understood and appreciated from the following description of a pre-

ferred embodiment thereof selected for purposes of illustration and shown in the accompanying drawings, in which,—

Figure 1 is a perspective view of portions of an eyeleting machine having the present invention embodied therein; 55

Figs. 2 to 5 show the punching and setting tools in the successive positions occupied by them during the cycle of the machine;

Fig. 6 is a plan view showing the position of the upsetting die in an upper; 60

Fig. 7 is a view in perspective of the upsetting die.

The invention is herein disclosed as embodied in the machine of an application of P. R. Glass, Serial No. 855,185, filed August 5, 1914. Such parts of the machine as are not herein shown may be of the same construction as corresponding parts illustrated in said application. It will be understood, however, that the invention is not limited in its application to this or to any particular type of eyeleting machine. 65 70

The frame 10 is provided with two pair of horizontal bearings in the upper of which is received a stationary guide rod 12 and in the lower of which slides a movable guide rod 14. A transversely movable head 16, slides upon the upper rod 12 and is fast to the lower rod 14. The movement of the head 16 is thus limited to a horizontal path. 80

The head 16 is provided with vertical bearings for a plunger 18 carrying at its lower end a cylindrical tubular punch 21. The plunger is reciprocated vertically by an eccentric and other mechanism not herein shown. In the lower portion of the frame are provided bearings for a vertically movable plunger having at its upper end the lower or eyelet inserting die 40 and a center spindle 42 for picking successive eyelets from a raceway 38. The inserting die 40 is arranged to pass through an opening in a stationary work plate 34 which is mounted upon the machine frame. The parts of the machine thus far described, with the exception of the punch, are similar to the corresponding parts of the machine of the application above identified. 85 90 95

The movable head 16 carries a frame 24 which is pivotally mounted to swing about the axis of the plunger 18. The upper and lower branches of the frame are secured together by a rod 26 having a removable hand nut at its upper end. When it is desired to remove the frame from the head 16 the rod 26 is loosened and the two branches of the frame are swung apart and slipped off of their journals. Suspended from the lower side of the frame 24 is a horizontally disposed bar 28 carrying at its inner end an upsetting die 32 facing downwardly. The bar 28 is of a yielding character and, in order to adjust the vertical position of the upsetting die, there is provided an adjusting bolt 30 by which the inner end of the bar 28 may be raised or lowered. The inner end of the bar 28 is formed with an opening which constitutes a punching die to coöperate with the cylindrical punch 21. The punching die opening, as shown in Fig. 7, passes through the center of the upsetting die 32. A stationary cutting block 35 is secured to the frame in an opening formed in the work table 34 and is located in alignment with and beneath the punch when the latter occupies its initial position. The construction and arrangement of these parts is such that the punch 21 may pass entirely through the opening in the punching die and coöperate with the cutting block 35 to perforate work located beneath the punching die.

35 A presser foot 36 is provided to clamp the work to the work table 34 during the reverse movement of the head 16. The presser foot as shown in Fig. 1, is provided with an arched portion beneath which extends the end of the bar 28, acting to clamp the work to the table. The presser foot therefore will engage the work at opposite sides of the bar 28 but will not clamp the work against the bar.

40 In setting invisible eyelets in a shoe upper the upper is presented to the machine with its outer or leather part 50 above the bar 28 and with its lining part 52 resting on the cutting block beneath the end of the bar.

45 In handling a right quarter the frame 24 is swung toward the right side of the machine as this facilitates reaching the point at which it is desired to set the uppermost eyelet. The position of the bar 28 which carries the upsetting die is shown in Fig. 6. Having presented the upper, the machine is set in operation whereupon the plunger 18 immediately descends and the outer part 50 of the upper is perforated by the punch and die action which takes place between the outer surface of the punch 21 and the punching die. The punch 21 passes entirely through the punching die and perforates the lining part 52 upon the cut-

ting block 35. Fig. 3 illustrates the punch 65 in this position. The plunger 20 is then elevated slightly to release the pressure on the cutting block 35 and the head 16 moved toward the left, thus feeding the hole in the upper into alignment with and above the eyelet inserting tool 40. This position of the tool is illustrated in Fig. 4. The lower plunger has been meanwhile elevated sufficiently to pass the spindle 42 through the endmost eyelet in the raceway 38 and the raceway has been retracted leaving the eyelet in place upon the set 40. In the next step of the cycle the upper plunger 18 is depressed and the inserting die is elevated forcing the eyelet barrel through the hole 80 in the lining part of the upper and clenching it against the upsetting die 32. The punch 21 at the same time is depressed sufficiently to bring its shoulder against the surface of the outer part of the upper so as to reinforce the bar 28 against the pressure of the inserting die. In this operation the punch 21 which is of the same diameter as the spindle 42 forces the spindle downwardly into the inserting die.

90 During the feeding operation the presser foot 36 is lifted but at the conclusion of the setting operation the presser foot is lowered to hold the work stationary upon the work plate 34. The plunger 18 is then lifted, the lower plunger 39 depressed and the head 16 and its associated parts returned toward the right to initial position.

95 In setting blind eyelets the operation is the same as above described except that the upper is presented to the machine with the lining side uppermost, or in a position reversed from that shown in Fig. 6.

Having thus described my invention, I claim as new and desire to secure by Letters Patent:

1. A machine for inserting blind or invisible eyelets, having, in combination, a transversely movable head carrying a co-operating punch and punching die, said punch and die being relatively movable to perforate the work and then movable transversely with the head to feed the work while the punch remains in the punching die.

110 2. A machine for inserting blind or invisible eyelets, having, in combination, a transversely movable head carrying a co-operating punch and punching die, an upsetting die also carried by the head, said punch and die being relatively movable to 115 perforate the work and then movable transversely while the punch remains in the punching die to feed the work; and means for inserting an eyelet and clenching it on the upsetting die.

120 3. A machine for inserting blind or invisible eyelets, having, in combination, a transversely movable head, a punch and

5 punching die carried by the head and co-operating to perforate one part of a shoe upper, and a cutting block arranged to co-operate with the punch after the punch has passed through the punching die, whereby another part of the upper may be perforated.

10 4. A machine for inserting blind or invisible eyelets, having, in combination, a transversely movable head carrying a punch and a co-operating punching die, a cutting block, and means for moving the punch to perforate two layers of material located upon opposite sides of the punching die by 15 co-operation with said die and said block, the head being thereafter moved to feed the material.

20 5. A machine for inserting blind or invisible eyelets, having, in combination, a punch, a co-operating cutting block, an intermediate punching die, said punch being movable through the punching die to perforate one layer of material and into engagement with the block to perforate the 25 other layer, and means for inserting an eyelet in one of the layers so punched.

30 6. A machine for inserting blind or invisible eyelets, having, in combination, a transversely movable head, a punch mounted for longitudinal movement in the head, a frame arranged to swing about the axis of the punch, and having a punching die disposed in alignment with the punch, and co-operating setting tools one of which is carried by the frame.

35 7. A machine for inserting blind or invisible eyelets, having, in combination, a reciprocating eyelet inserting tool, a head movable transversely with respect to the path of the tool, and a pivotally mounted frame carried by the head and having an upsetting die arranged to be located in alignment with the tool when the head occupies a position at one end of its path.

40 8. A machine for inserting blind or invisible eyelets, having, in combination, a reciprocating eyelet inserting tool, an upsetting die, a support for the die mounted for movement about the axis of the die and including a long thin bar arranged to be inserted edgewise between the outer and lining parts of an upper, and a punching tool arranged to co-operate with said bar for perforating the work.

45 9. A machine for inserting blind or invisible eyelets, having, in combination, a head having spaced bearings for a vertically movable punch, a frame journaled upon the bearings for the punch to swing horizontally, and a die carrying bar suspended below the frame.

50 10. A machine for inserting blind or invisible eyelets, having, in combination, a work table, a presser foot having an arched

portion, and a thin die carrying bar arranged to pass through the arched portion of the presser foot and to clamp the work to the table.

55 11. A machine for inserting blind or invisible eyelets, having, in combination, a transversely movable head, a longitudinally movable punching tool mounted in the head, a punching die mounted below the head and having an upsetting surface on its side facing away from the head and being constructed to be introduced between the outer and lining parts of a shoe upper, said punch acting to perforate the outer part by entering the punching die, a cutting block with which the punch then co-operates, and an inserting tool arranged to insert an eyelet through the lining part of the upper and clench it on the upsetting die.

60 12. A machine for inserting blind or invisible eyelets, having, in combination, a work table, a punch movable above the work table, a punching die member having an upsetting die on one face disposed above the work table, and means for adjusting the punching die member with respect to the table.

65 13. A machine for setting blind or invisible eyelets, having, in combination, a movable punching member 21, and two stationary members with which said punching member co-operates successively to form respectively pairs of co-operating punching elements.

70 14. A machine for setting blind or invisible eyelets, having, in combination, a punching die, a cutting block, a movable punching member shaped to act as the male member of a punch and die combination, and as a cutting punch in combination with said cutting block, and means for setting an eyelet in the work.

75 15. A machine for inserting blind or invisible eyelets, having, in combination, a head having bearings for a vertically movable punch, a frame journaled in the head to swing horizontally about the axis of the punch, and an arm arranged to co-operate with the punch suspended from and below the frame.

80 16. A machine for inserting blind or invisible eyelets, having, in combination, a laterally movable head, an operating tool axially movable in said head, another axially movable operating tool, a thin bar having opposite surfaces thereof constructed and arranged to co-operate with said tools respectively, and means for pivotally supporting said bar in position with its operating end in alignment with one of said tools.

85 17. A machine for inserting blind or invisible eyelets, having, in combination, a laterally movable head, an operating tool axially movable in said head, another axially

4
movable operating tool, a thin bar having opposite surfaces thereof constructed and arranged to coöperate with said tools respectively, and means for supporting said bar on said head with its operating end in alinement with the tool carried thereby so that the work may be fed by lateral movement of

the head while its tool and the bar are in co-operating relation with one another and with the work.

10

In testimony whereof I have signed my name to this specification.

GEORGE P. CLARK.
